SIGNORS TO CHIKSAN OIL TOOL CO., LIMITED, A CORPORATION OF NEVADA

DRILLING BIT

Application filed February 7, 1929. Serial No. 338,084.

This invention relates to a rotary drill and relates particularly to a drill for use in drilling wells with the rotary method.

It has been found that cutters of rotary well drilling bits, and especially the disk type of cutters, wear rapidly during drilling operations. As the cutters wear, they become reduced in size or diameter, and fail to cut or drill a hole of the desired size.

10 It is a primary object of this invention to provide a rotary drill in which the cutters will not readily mud up. The cutters in the present drill are arranged in pairs and the cutters of each pair work relative to each other so that they keep themselves clean.

It is another object of the invention to provide a rotary drill in which certain cutters engage the bottom of the hole while the other cutters on the same mountings engage 20 only the wall of the hole.

It is another object of the invention to provide a drill of the character mentioned in which a plurality of cutters are mounted on the same pin so that they rotate eccentrically 25 and independently of one another.

The various objects and features of our invention will be best and more fully understood from the following detailed description of a typical preferred form of the invention, throughout which description reference is had to the accompanying drawings, in which:

Fig. 1 is a side elevation of the device provided by this invention. Fig. 2 is a bottom plan view showing the relative positions of the cutters in the preferred form of the invention. Fig. 3 is an enlarged detailed sectional view taken as indicated by line 3—3 on Fig. 1, and Fig. 4 is an enlarged detailed 40 sectional view taken as indicated by line 4—4 on Fig. 3.

The drilling bit provided by this invention includes, generally, a body or shank portion 10 having a screw-threaded pin 11 at its upper end for connection with a string of drill pipe, a plurality of spaced arms 12 and 13 arranged in pairs and projecting from the lower end of the shank portion, bushings 14 mounted between each pair of arms 12 and 13, pins 15 carried by and extending between the arms 12

and 13 of each pair and operating to carry the bushings, and disk cutters 16 rotatably carried on the bushings.

The shank portion 10 is elongated and is preferably round in cross section. In the form of the invention illustrated in the drawings the shank is provided near its upper end with an enlarged part forming a downwardly facing shoulder 17 adapted to be engaged by a fishing tool to facilitate the removal of the bit from a well bore in the event the bit becomes lost in the well. The pin 11 projects from the upper end of the shank 10 and is tapered and screw threaded as shown in the drawings. A fluid circulation opening 18 extends longitudinally through the shank and discharges at the center of the lower end of the shank portion. The lower end of the opening 18 is provided with a detachable nozzle bushing 19 preferably screw threaded into the lower end of the opening.

The arms 12 and 13 extend downwardly and radially from the lower end of the shank portion 10 and are preferably formed integral with the shank portion. In the form of

75 the invention illustrated the lower end of the shank 10 is enlarged so that the arms 12 and 13 are readily formed integral with the shank and are of relatively heavy and sturdy construction. The arms are in pairs, each pair including an upper arm 12 and a lower arm 13. There may be any desired number of pairs of arms. In the preferred form of the invention shown we provide three pairs of arms symmetrically disposed around the central longitudinal axis of the bit. The pairs of arms 12 and 13, being equally spaced and symmetrically disposed around the central longitudinal axis of the shank 10, carry the cutters 16 so that they operate to center 80 the bit in the well bore during operation. The arms 12 and 13 are in spaced parallel relation to each other and are similarly disposed with relation to the central longitudinal axis of the shank.

95 In practice we prefer to pitch the arms at approximately 45 degrees with reference to the vertical axis of the bit. The lower ends of the arms may be beveled or dressed off to allow material to clear the cutters 16. The 100

lower arms 13 are preferably beveled as shown at 20 in the drawings to be at approximately 90 degrees to the vertical axis of the shank 10, while the lower end of the upper arm 12 is beveled as at 21 so as to be substantially parallel to the vertical axis of the shank 10. With this beveling of the arms, there is ample clearance for the passage of cuttings and circulation fluid. The outer edges of the arms may be also beveled as shown in the drawings to further provide for the passage of cuttings and circulation fluid.

The bushings 14 are carried on the pins 15 between the pairs of arms to carry the cutters 16 so that they are disposed between the arms 12 and 13 and in planes parallel to those of the arms. The cutters have their cutting edges extending downwardly and radially outward beyond the lower ends and sides of the arms to engage the bottom and the side walls of the well bore. In accordance with the broad spirit of the invention there may be a unitary bushing member disposed between each pair of arms 12 and 13 to carry a pair of cutters 16. In the preferred form of the invention we provide two separate parts or bushings between each pair of arms 12 and 13, each bushing carrying a cutter. The bushings are arranged so that their inner sides 22 abut or bear on each other while their outer sides 22^a engage the inner surfaces 23 and 24 of the arms 12 and 13, respectively. Each bushing is provided with an exterior cylindrical bearing surface 25 to rotatably carry a cutter and is provided at its outer end with a radially projecting flange 12^b. The flanges 12^b operate to space the cutters from the inner faces 23 and 24 of the arms. The bushings are mounted stationary, or held against movement relative to the arms, so that all wear, due to the rotation of the cutter, occurs between the cutters and the bushings. In the form of the invention illustrated the outer ends of the bushings are provided with transverse projecting key parts 26 which fit into corresponding recesses or slots 30 in the inner faces 23 and 24 of the arms. The key parts are disposed so that the bushings can be easily slid into place between the arms and operate to positively prevent rotation of the bushings when the bushings are in operating position.

The bushings are mounted on pins 15 which extend through and between the arms 12 and 13. The pins extend through openings 46 in the bushings. The axes of the openings 46 are offset or eccentric to the bearing surfaces 25. The eccentricity of the openings 46 in the two bushings between each pair of arms may be substantially the same or may vary or be different as circumstances require. In the preferred form of the invention shown in the drawings the eccentricity of the openings 46 is the same in all of the bushings. The two bushings between each pair of arms are mounted on the sup-

porting pin 15 so that the cutter carrying bearing surfaces are offset in different directions from the axis of the pin. In the preferred arrangement illustrated the two bushings are mounted on the pin 15 so that the axes of the bearing surfaces 25 are offset in diametrically opposite directions. It is advantageous to arrange the bushings so that the lower bushing is offset downwardly and the upper bushing offset upwardly. This throws the lowermost cutter of each pair of cutters downwardly so that it is well below the upper cutter and therefore does the cutting on the bottom of the hole. The upper cutter is clear of the bottom of the hole but projects radially outward and is located above the lower cutter so that it cuts the side of the hole, keeping the hole to gauge. The cutters are free to rotate independently of one another on the bushings and during operation they move or work relative to each other so that they do not become muddled up.

The pin 15 extends through an opening 34 in the upper arm 12 and is screw threaded into an opening 35 in the lower arm 13. The pin is provided with a polygonal head 36 which seats against the outer side of the upper arm 12. In the construction provided by this invention the pin 15 has no tendency to rotate and thus become loosened or disengaged from the threaded opening 35. The pin 15 may be locked or further secured by suitable means, if so desired.

The cutters 32 and 33 are disk type cutters each having a central opening 37 to receive a bushing. The peripheral edge of each cutter is beveled off to form a suitable cutting edge. In the drawings the peripheral edge 38 of each upper cutter is beveled off at substantially 45 degrees to form a cutting edge. The upper cutter engages the side wall of the well hole and is therefore beveled or dressed so that it has an edge 39 effective at the side of the hole. This can be had by dressing and arranging the cutter as shown in the drawings. The periphery of the lower cutter 33 is beveled so that it is substantially vertical and forms a cutting edge 41. The lower cutter normally engages the bottom of the well bore and the edge 41 is in position to effectively cut the formation at the bottom of the bore.

In the preferred construction the cutters are counter bored at 85 so that the bushings seat in the cutters. This gives the cutting parts maximum clearance and permits the use of thick cutters.

Having described one pair of arms and the bushings, pin, and cutters carried by the arms, it is apparent that such description applies to each cutter unit embodied in the bit. It will be apparent that such cutter assemblies, symmetrically arranged as illustrated, provide a bit which is simple, effective, and

practical. It is to be particularly noted that the upper cutters and the lower cutters of the several pairs of cutters operate to separately cut the wall of the well and the bottom of the well, that is, the upper cutters engage only the walls of the well while the lower cutters engage principally the bottom of the well. The lower cutters may wear more rapidly than the upper cutters and become smaller in diameter than the upper cutter and thus drill a hole of reduced diameter, however, as the bit is fed downwardly the upper cutters engage the wall of the hole and cut it to the desired size. As the lower cutters become worn, the upper cutters take a larger cut.

Having described only a typical preferred form of our invention, we do not wish to limit ourselves to the specific details set forth, but wish to reserve to ourselves any changes or variations that may appear to those skilled in the art or fall within the scope of the following claims:

Having described our invention, we claim:

1. A well drilling bit including, a shank, spaced arms projecting from the shank, bushings mounted between the arms, the bushings being held against rotation, each bushing having a cylindrical bearing part, and cutters rotatably mounted on the bearing parts so that they are inclined with reference to the longitudinal axis of the shank, the axes of said bearing parts being spaced apart and parallel with each other.
2. A well drilling bit including, a shank, spaced parallel arms projecting downwardly and radially from the shank, two bushings mounted between the spaced arms the bushings having cylindrical bearing parts, a pin extending between the spaced arms and through the bushings eccentric to the bearing parts, means holding the bushings against rotation so that the axes of the bearing parts are diametrically opposite, and cutters rotatably mounted on the bushings.

3. A well drilling bit of the character described including, a shank, a plurality of symmetrically arranged pairs of spaced arms projecting downwardly and radially from the shank, two bushings arranged between each pair of arms, each bushing having an exterior cylindrical bearing surface, a pin carried by each pair of arms and extending through openings in the bushings, the openings being eccentric to the exterior bearing surfaces, means for holding the bushings against rotation and in different rotative positions on the pin so that the bearing parts are eccentric to each other, said means including a key portion on each bushing extending into a recess in an arm and cutters rotatably mounted on the bearing parts.
4. A well drilling bit of the character described including, a shank, a plurality of symmetrically arranged pairs of spaced arms

projecting downwardly and radially from the shank and inclined relative to the vertical axis of the shank, two bushings arranged between each pair of arms, the bushings having cylindrical bearing parts, pins carried by the arms and extending through openings in the bushings, the openings being eccentric to the bearing parts, the bushings being arranged so that the bearing parts of the two bushings arranged between each pair of arms are eccentric to each other, means preventing rotation of the bushings, and cutters rotatably mounted on the bearing parts.

5. A well drilling bit including, a shank, spaced arms projecting from the shank, bushings arranged between the arms, cylindrical bearing parts on the bushings, a pin carried by the arms extending through openings in the bushings eccentric to the bearing parts, means holding the bushings against rotation, and holding them so that their bearing parts are oppositely disposed, an upper cutter rotatably mounted on one bearing part, and a lower cutter rotatably mounted on the other bearing part, the cutters being in engagement with each other.

6. A well drilling bit including, a shank, spaced arms projecting downwardly and radially from the shank, upper and lower bushings arranged between the arms, each bushing having a cylindrical bearing part, a pin carried by the arms extending through openings in the bushings eccentric to the bearing parts, an upper cutter rotatably mounted on the bearing part of the upper bushing, and a lower cutter rotatably mounted on the bearing part of the lower bushing, the periphery of the lower cutter being beveled so that its leading part is substantially vertical and the periphery of the upper cutter being beveled so that its leading part is substantially horizontal, and means holding the bushings so that the bearing parts are eccentric to each other.

7. A well drilling bit including, a shank, spaced arms projecting from the shank, bushings mounted between the arms, means holding the bushings against rotation, a cylindrical bearing part on each bushing, the axes of said bearing parts being spaced apart and parallel with each other, cutters rotatably mounted on the bearing parts so that they are inclined with reference to the vertical axis of the shank, and flanges on the bushings spacing the cutters from the arms, the flanges being recessed in the cutters.

8. A well drilling bit of the character described, including a shank, spaced arms on the shank, bushings carried between the arms and having cylindrical bearing parts, a pin extending through the arms and through openings in the bushings, the openings in the bushings being eccentric to the bearing parts, means holding the bushings against

rotation so that the bearing parts are eccentric to each other, said means including a transverse key projection on each bushing, each projection extending into a recess in one of the arms, and cutters rotatably carried by the bearing parts and inclined with reference to the longitudinal axis of the shank.

In witness that we claim the foregoing
10 we have hereunto subscribed our names this
24th day of January, 1929.
